CLAIM

The ornamental design for a milking claw for a milking machine, as shown and described.

DESCRIPTION

FIG. 1 is a perspective view of a milking claw for a milking machine according to a first embodiment of the design;

FIG. 2 is a right side view thereof,

FIG. 3 is a left side view thereof,

FIG. 4 is a front view thereof,

FIG. 5 is a back view thereof,

FIG. 6 is a top view thereof, and

FIG. 7 is a bottom view thereof.

FIG. 8 is a perspective view of a milking claw for a milking machine according to a second embodiment of the design;

FIG. 9 is a right side view thereof,

FIG. 10 is a left side view thereof,

FIG. 11 is a front view thereof,

FIG. 12 is a back view thereof,

FIG. 13 is a top view thereof; and,

FIG. 14 is a bottom view thereof.

Broken lines and unshaded portions contained within broken lines depict portions of the milking claw for a milking machine that form no part of the claimed design but are shown for purposes of illustration.
